FOREIGN PATENT DOCUMENTS

WO WO 00/17849 3/2000

Primary Examiner — Ian Simmons*Assistant Examiner* — Carissa C Fitts(74) *Attorney, Agent, or Firm* — Law Office of William Gustavson, PC(57) **CLAIM**

The ornamental design for a combination light and IR detector, as shown and described.

DESCRIPTION

FIG. 1 is a perspective top view of a first embodiment of a combination light and IR detector embodying my design, the head strap shown in dotted line forming no part of the present invention, the combination light and IR detector being suitable for use by a dentist or surgeon;

FIG. 2 is a front view of the first embodiment;

FIG. 3 is a right side view of the first embodiment;

FIG. 4 is a left side view of the first embodiment;

FIG. 5 is a back view of the first embodiment;

FIG. 6 is a top view of the first embodiment; and,

FIG. 7 is a bottom view of the first embodiment.
